ATTORNEY.

UNITED STATES PATENT OFFICE

154,687

DESIGN FOR A COMBINED WATCH AND COSMETIC CASE

Henry L. Lambert, New York, N. Y.

Application June 26, 1948, Serial No. 147,240

Term of patent 14 years

(Cl. D86—10)

To all whom it may concern:

Be it known that I, Henry L. Lambert, a citizen of the United States, residing in the county of New York, city of New York, and State of New York, have invented a new, original, and ornamental Design for a Combined Watch and Cosmetic Case, of which the following is a specification, reference being had to the accompanying drawing, forming part thereof.

Fig. 1 is a view in elevation of a combined watch and cosmetic case, showing my new design;

Fig. 2 is a top plan view thereof;

Fig. 3 is a perspective view thereof.

I claim:

The ornamental design for a combined watch and cosmetic case, as shown.

HENRY L. LAMBERT.
